UNITED STATES PATENT OFFICE

MARIE A. KIRKPATRICK, OF GRAND RAPIDS, MICHIGAN, ASSIGNOR TO FALCON MANUFACTURING CO., OF BIG RAPIDS, MICHIGAN, A CORPORATION OF MICHIGAN

DESIGN FOR A SAXON WHEEL TABLE

Application filed October 5, 1931. Serial No. 41,307. Term of patent 7 years.

To all whom it may concern:

Be it known that I, MARIE A. KIRKPATRICK, a citizen of the United States, residing at the city of Grand Rapids, in the county of Kent and State of Michigan, have invented a new, original, and ornamental Design for a Saxon Wheel Table, of which the following is a specification, reference being had to the accompanying drawings, forming a part thereof.

Fig. 1 is a perspective view of a table showing my new design, and

Fig. 2 is a side elevation of the same.

I claim:

The ornamental design for a saxon wheel table, as shown.

MARIE A. KIRKPATRICK.
